UNITED STATES PATENT OFFICE.

JAMES M. SANDERS, OF MORRISVILLE, OHIO.

CULTIVATOR TONGUE AND SHOVEL.

SPECIFICATION forming part of Letters Patent No. 355,104, dated December 28, 1886.

Application filed August 31, 1886. Serial No. 212,307. (No model.)

To all whom it may concern:

Be it known that I, JAMES M. SANDERS, of Morrisville, in the county of Clinton and State of Ohio, have invented a new and useful Improvement in Cultivator Tongues and Shovels, 5 of which the following is a full, clear, and exact description.

This invention consists in a cultivator-shovel, forming a combined tongue and shovel 10 of peculiar construction and capable of being adjusted laterally from a fixed center or pivot, substantially as hereinafter described, and pointed out in the claims.

Reference is to be had to the accompanying 15 drawings, forming a part of this specification, in which similar letters of reference indicate corresponding parts in all the figures.

Figure 1 represents a side or edge view of a combined tongue and shovel, together with 20 the standard of the plow or machine to which it is attached. Fig. 2 is a top view of the same. Fig. 3 is an under view thereof; and Figs. 4 and 5 are transverse sections upon the lines *x*-*x* and *y*-*y*, respectively.

25 A and B indicate the blade, the portion marked A more particularly representing the tongue part and B more particularly what may be termed the "shovel" part thereof. The one side, *b*, of the blade is made straight throughout its length from *c* to *d*, and is beveled on 30 its under surface, as at *e*, to make said side or edge a cutting one. This construction adapts the blade to first plowings. The lower or point end, *f*, of the blade from *d* to *g* is made 35 to form an acute angle with the edge *b*, and is also beveled on its under surface, as at *e'*, to give it a cutting-edge. This angular end construction near the edge *b* serves to work the earth closer to the plant, and the whole of 40 said end from *d* to *g* being made slanting, as shown, exerts a forcing action toward or from the plant. The other side or edge, *i* *i'*, of the blade opposite to *b*, from *g* to *h*, is straight below, as at *i*, but spreads out laterally and upwardly in a curvilinear direction, as at *i'*, and is beveled on its under surface, as at *e''*, to give 45 a sharp or cutting edge joining the beveled cutting-surface *e'*. This construction more especially provides for the surface of the ground being cultivated without disturbing the roots of the plant. Above the curved por-

tion *i'*, from *h* to *k*, the blade presents a rounded edge, *l*, the object of which is to prevent injury to the plant, and the surface or area of the blade on the side which is bounded by the 55 rounded edge *l* being greater, the main volume of dirt will pass off in that direction.

The whole blade is secured to the standard C by screw-bolts *m* *m'*, arranged one above the other, and having nuts *n* *n'* on the under or 60 back side of the standard. The one of these bolts, *m*, rests in a countersunk seat formed by the side walls of an oblong slot, *o*, running in direction of the width of the plate, to provide for a lateral adjustment of the latter from a 65 fixed center or pivot formed by the bolt *m'*.

The blade, as it will be seen, has its edges beveled from heel to point.

By means of the oblong hole *o*, bolt *m*, fitting therethrough, and the pivot or bolt *m'*, upon 70 which the blade is capable of being turned to adjust it laterally in opposite directions, as shown by dotted lines in Fig. 2, the point end of the shovel may be adjusted to or from the plant and the operator be enabled to plow 75 either close to the plant or away from it. The shovel or blade may be used either with its straight side next to the plant, as it is designed to do when the plant is small and needs the earth stirred close to it, but requires little 80 or no earth to be thrown toward the plant, or the shovel may be turned and its opposite or curved edge be presented to the plant, as it is designed to do when the plant needs the earth thrown to or toward it and the roots left undisturbed. By this reverse action of the plow there is much economy, the one shovel answering the purpose of two. Of course the point of the plow is always in front; but the shovel being beveled from heel to point, and being 85 laterally adjustable, as described, it always forms or presents an efficient cutting-surface, for when the point end of the shovel is in the ground, and the curved side or edge of the shovel is toward the plant, the surface of the 90 ground may be scraped and weeds be easily cut. Again, by reason of the sharp edges of the shovel from heel to point, it can be more readily shifted while in the ground, as there will always be a sharp edge to cut its way, and 95 hence it can be more easily managed than if the side edges of the shovel were square and 100

blunt. Furthermore, the rounded surface or edge l above the sharp curved edge l' protects the plant from injury, for when the corn or plant of any kind is large, and the plow happens to strike it, said rounded surface will leave the plant uninjured, whereas a square side would cut the plant and damage it.

Having thus fully described my invention, I claim as new and desire to secure by Letters 10 Patent—

1. The herein-described tongue and shovel, consisting of the apertured and slotted blade A B, having the straight beveled edge b , an opposite partly straight and curved beveled edge, $i i'$, terminating in an upper blunt edge, l , and the lower inclined and beveled front end edge, f , substantially as specified.

2. The combination, with the standard C and bolts $m m'$, of the blade A B, adapted to swivel or turn upon the bolt m , and having a transverse slot, o , adapted to receive the bolt m' , and constructed with a straight beveled edge, b , an opposite partly straight and curved beveled edge, $i i'$, terminating in an upper blunt edge, l , and the lower inclined and beveled front edge, f , essentially as shown and described, and for the purposes herein set forth.

JAMES M. SANDERS.
